Patented October 11, 1904.

UNITED STATES PATENT OFFICE.

BENJAMIN J. TAYLOR, OF TOLEDO, OHIO.

DESIGN FOR A STOVE OR RANGE.

SPECIFICATION forming part of Design No. 37,183, dated October 11, 1904.

Application filed September 6, 1904. Serial No. 223,569. Term of patent 7 years.

To all whom it may concern:

Be it known that I, BENJAMIN J. TAYLOR, a citizen of the United States, residing at Toledo, in the county of Lucas and State of Ohio, 5 have invented a new, original, and ornamental Design for Stoves or Ranges, of which the accompanying drawing is a view in perspective. What I claim as new, and desire to secure by Letters Patent, is—

The ornamental design for a stove or range, to substantially as shown.

BENJAMIN J. TAYLOR.
